US0D1058440S

(12) **United States Design Patent** (10) Patent No.: **US D1,058,440 S**
(45) Date of Patent: ** Jan. 21, 2025

(54) **BICYCLE FRAME ELEMENT**

(71) Applicant: **Robert Bosch GmbH**, Stuttgart (DE)

(72) Inventor: **Quoc-Dat Nguyen**, Reutlingen (DE)

(73) Assignee: **Robert Bosch GmbH**, Stuttgart (DE)

(**) Term: **15 Years**

(21) Appl. No.: **29/771,833**

(22) Filed: **Feb. 25, 2021**

(30) **Foreign Application Priority Data**

Aug. 27, 2020 (EM) 008149561

(51) **LOC (15) Cl.** **12-11**

(52) **U.S. Cl.**

USPC **D12/114**; D12/111

(57) **CLAIM**

The ornamental design for a bicycle frame element as shown and described.

DESCRIPTION

FIG. 1 is a perspective view of a bicycle frame element showing my new design;

FIG. 2 is a left side elevational view of the bicycle frame element of FIG. 1;

FIG. 3 is a right side elevational view of the bicycle frame element of FIG. 1;

FIG. 4 is a front side elevational view of the bicycle frame element of FIG. 1;

FIG. 5 is a rear side elevational view of the bicycle frame element of FIG. 1;

FIG. 6 is a top side plan view of the bicycle frame element of FIG. 1; and,

FIG. 7 is a bottom side plan view of the bicycle frame element of FIG. 1.

The broken lines shown in the drawings illustrate portions of the bicycle frame element that form no part of the claimed design.

1 Claim, 7 Drawing Sheets
